UNITED STATES PATENT OFFICE

2,505,100

ADJUSTABLE STOOL

Richard R. Cramer, Dayton, Ohio

Application April 30, 1948, Serial No. 24,332

3 Claims. (Cl. 155—94)

1

My present invention comprises a novel construction of adjustable stool wherein the seat member is mounted for raising and lowering adjustments thereof relative to the supporting means therefor. Such stools are useful for the seating of a person at drafting tables, and for various purposes are useful to housewives in the kitchen, and clerks and cashiers who sit behind counters and cash registers in mercantile establishments and in various other circumstances.

It is an object of my invention to provide such a stool in which the seat member may be readily raised or lowered for adjustments to the desired height.

Another object of the invention is to provide improved means for enabling the raising and lowering adjustment of the seat member relative to its supporting means.

A further object of the invention is to provide improved control means for facilitating the raising and lowering operation of the seat member.

Another object of my invention is to provide means for adjustment of the seat member relative to the main supporting means, and control means therefor, which are of relatively simple construction, easy to operate, enable very rapid raising and lowering action, and provide for supporting adjustments of the seat member at exactly the desired height.

In accordance with my invention I provide a stool of the above type in which fluid pressure means is interposed between the seat member and the supporting means therefor, whereby the seat member is supported in its adjusted position upon a confined body of fluid, and valve means operative to permit fluid to pass into or out of the confining space during raising or lowering of the seat member and normally operative to maintain the fluid in the confining space for retaining the seat member at the desired adjustment. I provide control means for the valve means operative to condition the latter for permitting movement of the fluid into or out of the confining space for raising and lowering adjustment of the seat member relative to the supporting means.

In accordance with my invention I contemplate the provision of spring means interposed between the supporting means and the seat member and operative to effect raising movement of the latter subject to the control of the valve means. The said valve means includes a freely movable valve member automatically movable to different valve closing positions under normal conditions when the control means is not being

operated. In one of the valve closing positions the seat member is prevented from being raised by action of the spring means when there is no weight on the seat member. In the other valve closing position the seat member is prevented from being lowered by downward pressure thereon. The automatic movement of the valve member from one to the other of the said valve closing positions serves to maintain the seat member in the adjusted position.

Other objects, advantages, and features of the invention will appear from the following detail description taken in conjunction with the accompanying drawing, in which

15 Figure 1 is a side elevation of the stool embodying my invention, parts being shown in section and illustrating the means for adjustably supporting the seat member relative to its supporting means, including the fluid pressure means, the spring means, the valve means, and the control means for the latter.

20 Figure 2 is an enlarged detail sectional view of a portion of the device illustrating more particularly the operation of the valve means and showing the valve member moved to neutral position by operation of the control means for raising or lowering movement of the seat member relative to its supporting means.

25 Figure 3 is a view similar to Figure 2 but illustrating the normal condition of the valve means when the control means is not being operated, the valve member being shown in full lines as when positioned in one of its valve closing positions, and said figure illustrating by dotted lines the positioning of the valve member in the other of its valve closing positions.

30 Figure 4 is an enlarged detail sectional view showing more particularly a portion of the control means.

35 Now referring to the drawings and describing the invention in detail, the stool illustrated comprises a seat member generally designated by the letter A and supporting means therefor generally designated by the letter B and comprising the legs 1, four of which are provided and suitably joined together to afford a rigid supporting frame structure. The legs 1 may be conveniently formed of metal tubing and secured together by means of a tubular ring 2 welded or otherwise suitably secured to the legs 1 adjacent the lower ends thereof. The upper ends of the legs 1 may be joined together by means of the cylindrical retainer member 3 to which the upper ends of the legs 1 are bolted or otherwise suitably secured.

2

Fluid pressure means is interposed between the seat member A and the supporting means B and comprises cooperating piston and cylinder elements associating the seat member A with the supporting means B for relative movement of said seat member upwardly and downwardly relative to said supporting member. To this end, the cylinder retainer member 3 has force-fitted into the bore thereof the cylinder 4, the lower end of which is closed as at 5 and provided with a 10 filler plug 6 for filling the cylinder with oil or other suitable fluid. The upper end of the cylinder 4 has a cap 7 through which the piston sleeve 8 extends. The piston sleeve 8 forms a part of the piston member generally indicated by the numeral 9 and the lower end of which is provided with the piston head 10 and the piston guide member 11, the elements 10 and 11 working within the cylinder 4. The cylinder cap 7 is provided with the sealing ring 12 of suitable resilient material engaging the piston sleeve 8 to prevent leakage of fluid from the cylinder 4. The piston guide member 11 has an annular groove 13 in which is received a similar sealing ring 14 of similar resilient material engaging the interior wall of the cylinder 4 to prevent leakage of fluid from the interior of the cylinder 4 below the guide member 11 to the interior of the cylinder above the guide member 11.

The cylinder 4 is designed to have fluid confined therein, and for this purpose a liquid 15, such as oil or the like, commonly employed in hydraulic devices, is availed of, said liquid 15 being introduced to the interior of the cylinder through the filling aperture closed by the filler plug 6. A portion of the liquid 15 is confined within the cylinder 4 below the guide member 11, which functions as a part of the piston head 10, and this confined body of liquid acting upon the piston head 10 and guide member 11 serves to support the seat member A at adjusted positions of movement upwardly and downwardly relative to the supporting means B. Valve means is provided which controls the passage of fluid from the interior of the cylinder 4 below the piston head 10, 11, to the interior of the piston sleeve 8 above the piston head 10, 11, and vice versa, said valve means being normally operative to prevent such flow of fluid and thus maintain a confined body of fluid below the piston head 10, 11 within the cylinder 4 for supporting the seat member A at its adjusted position. The valve means is subject to control by suitable control means to be described, to permit passage of fluid from the interior of the cylinder 4 below the piston head 10, 11 to the interior of the sleeve 8 above the piston head 10, 11 for enabling raising and lowering movement of the seat A relative to the supporting means B.

Now describing the valve means, the piston head 10 is provided with an interior valve chamber 16 in which is located the movable ball valve member 17. Communicating with the valve chamber 16 is a port or passage 18 leading from the chamber 16 to the interior of the piston sleeve 8 above the piston head 10. Communicating also with the valve chamber 16 is a port or passage 19 leading from the chamber 16 to the interior of the cylinder 4 below the guide member 11 portion of the piston head. The inner or chamber ends of the ports or passages 18 and 19 are suitably tapered as at 18a and 19a, respectively, to facilitate seating of the valve member 17 for closing of the ports 18 and 19.

The control means for the valve member 17

includes an actuating member or rod 20 having adjacent its lower end a portion 20a of reduced diameter and having a valve engaging head portion 20b at the extreme lower end thereof, the 5 said valve engaging head 20b being of larger diameter than the reduced shank portion 20a for ensuring engagement with the valve member 17. The valve engaging head 20b and a portion of the reduced shank 20a are normally adapted to lie within the passage 18 as shown in Figure 3 and may pass through said passage 18 into the chamber 16 as shown in Figure 2, the valve engaging head 20b being of slightly smaller diameter than the diameter of the passage 18 to permit 15 movement through the passage, and the reduced shank portion 20a being of considerably smaller diameter than the passage 18 to readily permit flow of fluid through the passage 18 to and from the chamber 16 when the actuating member is 20 positioned as shown in Figure 2, with the valve engaging head portion 20b disposed within the chamber 16. The reduced shank portion 20a is of sufficient length, longer than the length of the passage 18, to ensure that there will be unobstructed flow through the passage 18 to and 25 from the chamber 16 when the actuating member is moved downwardly to its extreme limit of downward movement with the head 20b engaging the valve member 17 to hold the latter against the bottom of the chamber 16 as shown in Figure 2.

The upper end of the actuating rod 20 slidingly extends through the bore of a plug 21 force-fitted into the upper end of the sleeve 8. Actuating rod 20 is biased upwardly to the position 35 shown at Figure 3 by means of spring 22 engaging washers 23 and 24 slidably mounted on rod 20, washer 23 being retained on rod 22 by nut 25 threaded onto rod 20. Plug 21 carries a flexible 40 sealing member 26 (on which washer 24 rests) closely fitting around rod 20 to prevent leakage of fluid from sleeve 8.

The upper end of the piston sleeve 8 is received in a suitable socket provided in the retaining 45 member 27 which is bolted or otherwise suitably secured to the seat member A, the sleeve 8 being retained in association with the socket portion of retaining member 27 by means of screws 28.

The control means also includes a manually 50 operable control member carried by the seat member A and comprising a rod 29 extending transversely through the hollow retaining member 27, said retaining member 27 being provided with upwardly and downwardly elongated slots 30 and 31 55 in the wall thereof and transversely or horizontally aligned for receiving the manual control rod 29 passing therethrough. For retaining the rod 29 in proper position, the same is provided with lugs 32 engageable with the retaining member exteriorly thereof. The slots 30 and 31 are so disposed that the rod 29 rests upon the nut 25 carried at the upper end of the actuating rod 20. A circular ring member 33 is suitably secured to the transverse rod 29 and is of a diameter approximating that of or slightly less than that of the seat member A, serving, in conjunction with the transverse rod member 9, to provide a manual control member which may be readily manipulated from any point around the stool. Lugs 34 60 are secured to the under side of the seat member A at various points and are provided at their lower ends with horizontally inwardly extending flange portions 34a engaging under the circular ring 33 for supporting same in position ready for actuation.

A coil spring 35 is provided in the lower end of the cylinder 4, one end of the spring 35 engaging the lower end of the cylinder 4, and the other end of the spring engaging the guide member 11 portion of the piston head, the said spring 35 biasing the piston 9 and seat member A carried thereby upwardly relative to the supporting means B.

In operation, fluid 15 is introduced to the interior of the cylinder 4, filling the space within said cylinder 4 below the guide member 11 portion of the piston head, and said fluid is introduced to the interior of the piston sleeve 8 at least to a height above the top surface of the plug 12 when the guide member 11 is in engagement with the top plug member 12. The spring member 35 is of course under compression at all times within the cylinder 4. Assuming that the seat member A is positioned at some point intermediate its limits of upward and downward movement and that the control means 20, 29, 33 is not being actuated, the seat member A will be supported at such position by the confined body of fluid 15 confined within the cylinder 4 below the guide member 11 portion of the piston head. If there is no weight being exerted upon the seat A, the force of the spring 35 tends to push the piston 9 upwardly, which, but for the operation of the valve member 17, would tend to cause leakage of fluid from the interior of the sleeve 8 through the valve passage 18, chamber 16, and valve passage 19 to the interior of the cylinder below the guide member 11 portion of the piston head, permitting the force of the spring 35 to raise the piston 9 and seat member A carried thereby. However, the tendency, under the condition mentioned, for fluid to move from the interior of the sleeve 8 through the valve means to the interior of the cylinder 4 below the guide portion 11 causes the ball valve member 17 to seat itself in the seat portion 18a of the port 19, thereby closing the latter port and preventing movement of fluid just referred to, so that the action of the spring 35 tending to raise the piston 9 and seat member A carried thereby is prevented (due to suction under guide member 11) by the automatic operation of the valve member 17 closing the port 19.

Now, if weight is exerted upon the seat member A as by a person sitting upon the same, this weight tends to push the seat member A and piston 9 downwardly relatively to the cylinder 4 against the action of the spring 35. This condition tends to force the fluid confined in the cylinder 4 below the guide member 11 portion of the piston head through the passage 19 into the chamber 16, unseating the valve member 17 from the port 19, the fluid tending to be forced from the chamber 16 through the passage 18 to the interior of the sleeve 8. This tendency of the fluid to be forced in the direction just mentioned causes the valve member 17 to be moved to the dotted line position of Figure 3, seating itself in the seat 18a, thereby closing the port 18, thus preventing downward movement of the piston 9 and seat A carried thereby, which downward movement tends to be caused by the weight of the person sitting upon the seat A. Thus, the piston 9 and seat A carried thereby will, under this condition, be supported by the body of fluid within the cylinder 4 confined below the valve member 17 seated in the seat 18a, closing the port 18.

Thus it will be seen that under either of the conditions just above described, the seat member A will be maintained in the position to which it

has been adjusted by reason of the automatic operation of the valve member 17.

When it is desired to raise or lower the seat member A to adjust the same to a different height relative to the supporting means B, the control means for the valve member 17 is actuated by engaging the ring 33 at any point in its circumference and lifting upwardly thereon. This will cause the control rod 29 to fulcrum against the upper end of one of the slots 30 or 31, causing the control rod 29 to exert downward pressure on the nut 25 and actuating member 20 against the action of the spring 22, causing the valve engaging head 26 to engage the valve member 17 and press the same downwardly against the bottom of the chamber 16, thereby maintaining both the ports 18 and 19 open for flow of fluid through said ports and through the valve chamber 16 in either direction. Under this condition the seat member A may be raised or lowered to its desired position, after which the control member 33 is released, leaving the valve member 17 free to move to close either of the ports 18 or 19, thereby to maintain the seat member A at the adjusted position. While the control means is being operated to cause the actuating member 20 to engage the valve member 17 to move the same to the neutral position shown in Figure 2 for raising and lowering movement of the seat member A, if the seat member A is raised fluid 15 will flow or move from the interior of the sleeve 8 through the passage 18, chamber 16, and port 19, to the interior of the cylinder 4 below the guide member 11, thereby increasing the height of the confined body of fluid in the cylinder 4 below the guide member 11. If, under the same condition of operation of the control means, the seat member A is lowered, fluid 15 will move from the interior of the cylinder 4 below the guide portion 11 in the opposite direction through the port 19, chamber 16, and port 18, to the interior of the sleeve 8.

It will be understood also that the action of the spring 35, when the valve member 17 is held in the neutral position of Figure 2 and there is no weight on seat A, is to raise the seat A so that the upward movement of the seat A is substantially accomplished by the above mentioned control manipulation of the control member 33 without exerting outside force to lift up the seat A. Similarly, a person sitting upon the seat A may cause lowering movement thereof by his weight accompanied by the aforementioned control manipulation of the control member 33.

Having thus described by invention, what I claim as new and desire to secure by Letters Patent of the United States, is:

1. A device of the class described, comprising, in combination, a movable seat member, stationary supporting means therefor, cooperating piston and cylinder elements, one of said elements being secured to said movable member and the other of said elements being secured to said supporting means, said cylinder having fluid therein to support the seat carrying element at different positions respecting said supporting means, said piston element being hollow and having a head working in said cylinder and said head having a passage providing fluid communication between the space below the piston head and the space in the piston above the head, valve means operable to prevent and to permit movement of fluid through said passage, and spring means arranged to bias the piston and cylinder elements for movement relatively to one another

when the valve means is conditioned to permit movement of fluid through said passage, said valve means including a valve chamber in said passage, and having ports communicating therewith, a valve member normally freely movable in said chamber to a position closing one of said ports for preventing movement of fluid through said passage in one direction upon application of force tending to cause relative movement of said elements in one direction, said valve member being also freely movable to another position closing another of said ports for preventing movement of fluid through said passage in an opposite direction upon application of force tending to cause relative movement of said elements in an opposite direction.

2. A device of the class described, comprising, in combination, a movable seat member, stationary supporting means therefor, cooperating piston and cylinder elements, one of said elements being secured to said movable member and the other of said elements being secured to said supporting means, said cylinder having fluid therein to support the seat carrying element at different positions respecting said supporting means, said piston element being hollow and having a head working in said cylinder and said head having a passage providing fluid communication between the space below the piston head and the space in the piston above the head, valve means operable to prevent and to permit movement of fluid through said passage, and spring means arranged to bias the piston and cylinder elements for movement relatively to one another when the valve means is conditioned to permit movement of fluid through said passage, the

said piston and cylinder elements being arranged for relative movement upwardly and downwardly and said spring means being arranged to bias the seat carrying element for movement thereof upwardly relative to the supporting means, said valve means including a valve chamber in said passage, and having ports communicating therewith, a valve member normally freely movable in said chamber to a position closing one of said ports for preventing movement of fluid through said passage from the space above said piston head to the space below the same, thereby preventing upward movement of the seat carrying element by action of said spring means, said valve member being also normally freely movable to another position closing another of said ports for preventing movement of said fluid through said passage from the space below said piston head to the space above the same for preventing downward movement of said seat carrying element upon application of force thereto tending to cause downward movement thereof.

3. A device as in claim 2, and control means operable to condition the valve means for permitting movement of fluid through said passage.
